UNITED STATES PATENT OFFICE.

GEORGE CALUORI, OF JERSEY CITY, NEW JERSEY, ASSIGNOR TO PENNSYLVANIA TEXTILE MILLS, INC., OF CLIFTON, NEW JERSEY, A CORPORATION OF NEW JERSEY.

DESIGN FOR A TEXTILE FABRIC.

Application filed May 10, 1927. Serial No. 21,917. Term of patent 7 years.

To all whom it may concern:

Be it known that I, GEORGE CALUORI, a subject of the King of Great Britain, residing in Jersey City, in the county of Hudson, State of New Jersey, have invented a new, original, and ornamental Design for a Textile Fabric, of which the following is a specification, reference being had to the accompanying drawing, forming part thereof.

The figure is a plan view of a textile fabric showing my new design.

I claim:

The ornamental design for a textile fabric substantially as shown.

GEORGE CALUORI.
